UNITED STATES PATENT OFFICE.

JOHN C. MILLER, OF WATERBURY, CONNECTICUT, ASSIGNOR TO THE MATHEWS & WILLARD MANUFACTURING COMPANY, OF SAME PLACE.

DESIGN FOR A LAMP-FOUNT HOLDER.

SPECIFICATION forming part of Design No. 22,422, dated May 9, 1893.

Application filed March 10, 1893. Serial No. 465,434. Term of patent 8½ years.

To all whom it may concern:

Be it known that I, JOHN C. MILLER, of Waterbury, in the county of New Haven and State of Connecticut, have invented a new Design for Lamp-Fount Holders; and I do hereby declare the following, when taken in connection with accompanying drawing and the letters of reference marked thereon, to be a full, clear, and exact description of the same, and which said drawing constitutes part of this specification, and represents a perspective view of a lamp-fount holder embodying my design.

My invention relates to a design for lamp-fount-holders, and consists in the configuration and ornamentation as hereinafter described, and shown in the accompanying illustration.

The main body of my design is bowl-shaped in its general outline, and consists of a series

of pear-shaped shields A, inclosed in leaf-like floriations, and separated by lattice-work B, the said shields and lattice-work merging at their lower edges into open work, made by leaf-like forms. The said bowl is surmounted by a vertical collar, composed of two plain horizontal bands C C, separated by rococo open work D, comprising small shields and leaf-like scrolls.

I claim—

The design for lamp-fount holders as herein described and shown.

In testimony whereof I have signed this specification in the presence of two subscribing witnesses.

JOHN C. MILLER.
